United States Patent Office

Des. 198,918
Patented Aug. 18, 196

198,918

BOOK END

Karl E. Biallas, Chicago, Ill., assignor to W. H. Miner,
Inc., Chicago, Ill., a corporation of Delaware

Filed June 21, 1962, Ser. No. 70,638

Term of patent 14 years

(Cl. D33—3)

Fig. 1

Fig. 2

Fig. 3

Fig. 4

FIGURE 1 is a perspective view of the book end showing my new design;

FIGURE 2 is a side elevational view;

FIGURE 3 is a plan view; and

FIGURE 4 is an end elevational view, looking from the left hand end of FIGURE 2.

The side elevational view not shown is substantially the same as FIG. 2 and the end elevational view not shown is substantially the same as FIG. 4 with the simulated half railway car and the horizontal base portion of the book end deleted.

I claim:

The ornamental design for a book end, as shown and described.
